DESIGN FOR AN EMBALMING TABLE

Otto J. Day, Toronto, Ontario, Canada

Application February 7, 1944, Serial No. 112,505

Term of patent 7 years

(Cl. D33—14)

To all whom it may concern:

Be it known that I, Otto J. Day, a subject of the King of Great Britain and resident of the city of Toronto, in the Province of Ontario, in the Dominion of Canada, whose post-office address is 392 Sherbourne Street, in the city of Toronto, Ontario, Canada, have invented a new, original, and ornamental Design for an Embalming Table, of which the following is a specification, reference being had to the accompanying drawing, forming part thereof.

In the drawing:

The end and back of the table, not shown, are substantially the same as the disclosures of the end and the front which are shown.

I claim:

The ornamental design for an embalming table, as shown.

OTTO J. DAY.
